Application March 26, 1940, Serial No. 326,085

2 Claims. (Cl. 81—5.1)

The present invention relates to improvements in pliers.

An important object of the invention resides in the provision of pliers having a pair of pivoted jaws with means therein for readily extracting glass, tacks, or other objects embedded beneath the surface of a pneumatic tire.

Another object of the invention aims to provide pliers including a pair of pivoted jaws having slidably mounted therein a serrated member adapted to be expelled and retracted upon opening and closing the jaws respectively for extracting various objects embedded beneath the surface of a pneumatic tire or the like.

A further object of the invention resides in the provision of pliers having the above characteristics in which novel means is employed within the handle of the pliers for actuating the slidable serrated members upon movement of said handle whereby various embedded objects are readily removed.

A still further object of the invention resides in the provision of pliers of this nature which are simple in construction, relatively inexpensive to manufacture, thoroughly efficient, reliable in use, and well adapted for the purpose for which they are designed.

The invention will be fully and comprehensively understood from a consideration of the following detailed description when read in connection with the accompanying drawings which form a part of the application.

In the drawings:

Figure 1 is a top plan view partially in section of a pair of pliers embodying the features of the present invention with the jaws thereof in closed position.

Figure 2 is a top plan view thereof with the jaws in opened position.

Figure 3 is a longitudinal sectional view taken substantially on line 3—3 of Figure 1.

Figure 4 is a vertical sectional view taken substantially on line 4—4 of Figure 1.

Figure 5 is an enlarged sectional view taken substantially on line 5—5 of Figure 1.

Figure 6 is a top plan view of a modified form of the invention.

Figure 7 is a longitudinal sectional view taken substantially on line 7—7 of Figure 6.

Figure 8 is an enlarged detail view of one of the jaws of the pliers with the slidable member in expelled position.

Figure 9 is a detail sectional view taken substantially on line 9—9 of Figure 7.

Figure 10 is a detail sectional view taken substantially on line 10—10 of Figure 7.

While the present invention has been primarily designed for use in extracting glass, tacks or other objects embedded beneath the surface of pneumatic tires, it is to be understood that with a slight modification it can be employed for sundry other uses as for example, the extraction of particles of teeth which are embedded below the surface of the gums of the human jaw, for the extraction of small broken bones, pellets or other objects during surgical operations which may have become lodged below the surface of the skin, for facilitating the picking out of certain predetermined wires from a bunch of numerous control wires commonly employed in an electric telephone system, for facilitating a quicker and easier retrieve of objects such as brass bolts or nuts which have become lodged within and between apparatus such as radio sets and the like, or is applicable in laboratories where the temperature of handling tools is very essential and, in the latter case, the slidable serrated jaws are to be heat treated and insulated from the outer jaws.

Referring to the drawings for a more detailed description thereof, and particularly Figures 1 to 5 inclusive, there is shown a pair of pliers constructed in accordance with the present invention and generally designated by the reference numeral 12, comprising jaw members 13 and 14 and integrally formed handles 15 and 16, respectively. The handles and integrally formed jaws are pivotally connected as indicated at 17 by conventional means comprising male and female screws 18 and 19, respectively, which extend through aligned openings 20 formed in ears 21 and 22, respectively, projecting from the handles 15 and 16, respectively, as more clearly shown in Figure 5 of the drawings. A tubular sleeve 23 surrounds the female member 19 and aids in maintaining the handles in properly spaced relation. This type of pivot construction is of conventional form and is well known in the art.

The handles and jaws, respectively, are substantially U-shaped in cross section with the handles diverging from the jaws to assume the shape shown in Figure 1 of the drawings when said jaws are in closed position. Each jaw slidably supports therein a slidable member and the handles have attached thereto the means for actuating the slidable members as will be herein-after more apparent. As afore indicated, the jaws 13 and 14 are U-shaped in cross section

and each jaw has mounted therein for slideable movement a member 24 and 25, respectively, formed with serrations 26, said members adapted to be extended to substantially the position shown in Figure 2 of the drawings upon compressing the handles 15 and 16, respectively. The handles are returned to their normal spreading position upon release of pressure thereon by means of a tension spring 27, the ends 28 and 29 of which are fixedly secured in the respective handles 15 and 16. Compressing the handles will compress the spring 27 and upon releasing pressure thereon, said spring will return the handles to their normal position, which position is shown in Figure 1 of the drawings. A pair of flat rod-like members 30 are pivotally attached as indicated at 31 to an ear 32 formed in each handle, the opposite ends of the members 30 being disposed in overlapping relation and having pivotally attached thereto as indicated at 33 a horizontally disposed member 34, the members 30 and 34, respectively, being in the form of links. A substantially U-shaped spring steel wire 35 is attached centrally of its ends with a pivot pin 36 carried on the free end of the link 34, each end of said wire 35 extending on opposed sides of the pivot connection 31 with the ends thereof welded or otherwise secured at 37 with the slideable jaw members 24 and 25, respectively. Thus the pivotal connection 31 forms a guide for the spring steel rod-like member 35. Compressing the handles 15 and 16 together will compress the spring 27 and, in addition thereto, collapse the links 30 to project forwardly the link 34 and member 35 and since the members 24 and 25, respectively, are attached to the member 35, said members will be extended beyond the outer ends of the jaws 13 and 14, respectively, the entire mechanism moving as a unit. Upon the release of pressure on the handles, the spring 27 will return said handles to normal position carrying with them the movable unit.

Referring more particularly to Figure 4 of the drawings, it will be noted that the slideable members 24 and 25 are wedge-shaped in cross section and slide within a similar shaped trackway formed in the jaws 13 and 14, respectively, and are thus prevented from accidental disengagement while permitting free sliding movement.

In the use of the pliers for removing, for example, an embedded tack within the surface of a pneumatic tire, the nose portion of the jaws 13 and 14 will first be inserted into the damaged section until contact is made with the embedded object. The handles 15 and 16 are then squeezed together to project the members 24 and 25 whereby the serrated portion of said members will automatically grip the embedded object, then a slight twist of the pliers and a release of pressure on the handles will retract the slideable members a sufficient degree for a gripping contact with the object whereby withdrawing the pliers will cause the removal of said object. The use of the pliers in the manner described will not materially damage the tread of the tire which commonly occurs when inserting a screw driver or other sharp instrument for removing embedded objects.

In the modified form of the invention shown in Figures 6 to 10 inclusive, the slideable jaw members and actuating means therefor are shown in use with a pair of gooseneck pliers, the same being generally designated by the reference numeral 38. This type of pliers is especially useful in retrieving articles lodged in places that

are not readily accessible to the straight jaw type of pliers. It will be observed, however, that a pair of curved jaws 39 and 40 are an integral part of the handles 41 and 42, respectively, and are pivotally connected as indicated at 43 in the manner previously described. As in the preferred form, a pair of links 44 are pivotally connected to the handles 41 and 42, respectively, and the free ends of said links are attached to a horizontally extending link 45 from which extends a U-shaped steel wire 46. A pair of serrated jaw members 47 are mounted for slideable movement in the jaws 39 and 40 and are adapted to be extended and retracted by compressing the handles 41 and 42 as in the preferred form. Disposed intermediate of the slideable member 47 and the end 48 of the wire 46 are a series of rollers 49 mounted beneath the shoulder of a trackway 50, said rollers adapted to be reciprocated within the trackway by action of the wire 46 when compressing the handles of the pliers to extend and retract the slideable members 47. Referring more particularly to Figures 7, 8 and 9 of the drawings, it will be noted that the rollers are united in pairs by means of links 51, said links being alternately disposed on opposed sides of the rollers so as to occupy a minimum amount of space within the trackway. It is to be understood that a trackway, and series of rollers therein, is formed in each jaw and that the ends 48 of the wire 46 are attached to each series of rollers, as indicated at 52.

Upon compressing the handles 41 and 42 to the dotted line position shown in Figure 6 of the drawings, the links 44 and 45 will urge the U-shaped wire 46 forwardly which in turn causes movement of the series of rollers 49 within the trackway to extend the members 47 beyond the ends of the jaws 39 and 40 to the position shown in Figure 8 of the drawings. The tension spring 53 will return the movable parts to their normal positions upon the release of pressure on the handles. The jaws 39 and 40 are, of course, extended to the dotted line position shown in Figure 6 of the drawings upon compressing the handles 41 and 42, said jaws being extended simultaneously with movement of the slideable members 47. As in the preferred form, the slideable members 47 are formed with serrated teeth 54 for gripping articles or objects being retracted.

The operation of the pliers in the modified form is substantially the same as that described in the preferred form, which is thought to be readily apparent when considering the accompanying drawings with the hereinabove description.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed is:

1. A pair of pliers of the character described, comprising a jaw member having an integral handle, a second jaw member and integral handle pivotally connected to the former, said jaw members and handles being substantially U-

shaped in cross section, said jaw members forming a trackway having members slidable therein, a series of rollers supported within said trackway and attached to said members, and means carried by said handles attached to said rollers for actuating said slidable members through said rollers.

2. A pair of pliers of the character described, comprising, a jaw member having an integral handle, a second jaw member and integral han- 10

5 dle pivotally connected to the former, said jaw members being curved at an angle with respect to said handles, a member slidably supported within each of said jaw members, a series of rollers supported within each of said jaw members and attached to said members, and means carried by said handles attached to said rollers for actuating said slidable members through said rollers.

ALVIN C. GARY.
